UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A COLUMN FOR LIGHTING FIXTURES.

Application filed April 2, 1927. Serial No. 21,442. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Column for Lighting Fixtures, of which the following is a specification, reference being had to the accompanying drawing, forming part thereof, in which—

Fig. 1 is a front view showing my new design;

Fig. 2 is an edge view showing the contour.

I claim:

The ornamental design for a column for lighting fixtures, as shown.

HERMAN ABRAMS.
